UNITED STATES PATENT OFFICE.

OTTO E. SZEKELY, OF HOLLAND, MICHIGAN.

WASHING MACHINE.

Application filed April 23, 1927. Serial No. 186,009.

This invention relates to washing machines and more particularly to the impeller or agitator thereof.

The object of the invention is to provide for a thorough agitation of the water and clothes in the tub of the machine, and thereby to accomplish the washing operation efficiently and quickly.

Another object is to prevent clothes from 10 massing and traveling in a mass with the impeller.

Another object is to provide an integral impeller the vanes of which are unconnected with each other except through a central 15 body member and which have a substantial clearance above the bottom of the tub so that they may whip through, and below and above the clothes.

And a further object is to provide a vane 20 connected at its inner end only with the body of the impeller, and which tapers to a blunt outer end, having an upwardly and outwardly inclined bottom edge which provides a substantial clearance above the bot- 25 tom of the tub.

In the accompanying drawings illustrating a selected embodiment of the invention

Fig. 1 is a sectional elevation of a wash- 30 ing machine tub and having my invention embodied therein.

Fig. 2 is a perspective view of the im- 35 peller.

Fig. 3 is a top plan view.

Fig. 4 is a sectional elevation of the im- 35 peller.

Referring to the drawings 5 is a tub which is provided with a top opening 6 to be closed by a lid or cover, not shown. A plate 7 is securely bolted to the bottom of the tub, over 40 an opening 8 therein, and it is provided with a tubular support 9 which projects up centrally in the tub to receive the driving shaft 10. The support has a bearing 11 at its bot- 45 tom and a bearing 12 at its top and both bearings are provided with suitable bushings.

The impeller or agitator comprises a tu- 50 bular body 13 having a plurality, preferably four, of vanes 14 which are integral with the body and extend radially therefrom. Each vane is wider at its inner end than at its outer end and tapers to a blunt outer end. The bottom edge 15 of each vane is inclined upwardly from the inner end to the outer end of the vane, and the top edge 16 of each 55 vane inclines downwardly from the inner end to the outer end of the vanes. Also each

vane is thicker at its lower edge than at its upper edge and tapers in thickness from bottom to top for strength. The inner end of each vane extends from, at or about the 60 bottom of the body to a point above the middle of the body and below the top there- 65 of, in the embodiment shown, so that the vanes will be located in substantially the lower half of the tub.

The impeller is arranged on the support and shaft and a plug 17 in the upper end of the body forms a thrust bearing for the shaft. A pin 18 passes through the body, plug and shaft and makes a driving con- 70 nection between the shaft and body. The support has a bearing 19 for the lower end of the body and it is provided with a suit- 75 able bushing.

The vanes are entirely free and uncon- 75 nected except at their inner ends when they merge into the body, and there is a substan- 80 tial clearance between the bottom edge of each vane and the bottom of the tub, which clearance increases towards the outer end of the vane due to the taper of the vane. This is important because the mass of clothes in the tub may rest on the bottom of the tub and the operation of the impeller provides a whipping action through the water and 85 clothes which promotes the washing opera- 90 tion and enhances the efficiency of the machine. The impeller makes a violent agi- 95 tation of water which is highly desirable. I prefer to use a multi-sided tub because it will produce greater agitation of the clothes and water, but a round tub may be used if desired. The bottom and top edges of the vane are curved at their ends so that the clothes will slide freely thereon.

My improved impeller is novel and simple in construction and efficient in operation. It imparts a violent agitation to the clothes and water without injury to the clothes. The shape and arrangement of the vane is 100 of particular importance in this and other types of impellers because it is entirely free at its bottom edge, and therefore embodies no support for the clothes, so that it may whip through the clothes and thoroughly 105 agitate them. The impeller does not move the clothes as a mass which travels with the impeller, but the vanes whip through the clothes, keep the clothes open and in complete agitation, and pass over and through 110 and under the clothes.

I have described the invention in a form

which has been found satisfactory in actual use, but I do not restrict the invention to this particular embodiment for it will be apparent that it is of a greater scope. For example, the vane construction may be embodied in impellers of the type disclosed in my Patent No. 1,646,174 patented October 18, 1927, and in other types of impellers, and other changes in the form, construction and arrangement of parts may be made within the scope of the following claims:

I claim:

1. An integral impeller for washing machines comprising a central support, a plurality of relatively long, narrow, thin, tapered, imperforate and disconnected vanes radially extending from the support at the

lower portion thereof, the upper edges of said vanes being straight and inclining slightly downward from the support, the lower edges of said vanes being straight and inclined upward from said support, the outer ends of said vanes being substantially parallel with the support and having rounded corners, and the inner ends of the top and bottom edges of the vanes curving sharply upward and downward, respectively, and merging with the support.

2. An integral impeller for washing machines as described in the preceding claim with the lower edges of the vanes inclined upward at a sharper angle than the downward inclination of the upper edges.

OTTO E. SZEKELY.
